UNITED STATES PATENT OFFICE

117,197

DESIGN FOR A SIGNAL LAMP

John C. Schellin, Jesse M. Love, and Earl J. Housekeeper, Wooster, Ohio, assignors to Akron Brass Manufacturing Company, Inc., Wooster, Ohio, a corporation of Ohio

Application August 11, 1939, Serial No. 86,620

Term of patent 7 years

To all whom it may concern:

Be it known that we, John C. Schellin, Jesse M. Love and Earl J. Housekeeper, citizens of the United States, residing at Wooster, in the county of Wayne and State of Ohio, have invented a new, original, and ornamental Design for Signal Lamp, of which the following is a specification, reference being had to the accompanying drawing, forming part thereof.

Figure 1 is a side perspective view of a signal lamp embodying my new design; and

Fig. 2 is a front perspective view thereof.

We claim:

The ornamental design for a signal lamp, as shown.

JOHN C. SCHELLIN.
JESSE M. LOVE.
EARL J. HOUSEKEEPER.
